ATTORNEY.S.

UNITED STATES PATENT OFFICE

WALTER M. HANSON, OF GRAND RAPIDS, MICHIGAN, ASSIGNOR TO AMERICAN SEATING COMPANY, OF GRAND RAPIDS, MICHIGAN, A CORPORATION OF NEW JERSEY

HINGE

Application filed November 3, 1930. Serial No. 492,940.

The present invention relates to hinges and more particularly to seat hinges.

The main objects of the invention are to provide a seat hinge for use in conjunction with seats such as opera chairs and the like; to provide a hinge which is adjustable with respect to arcuate seating; to provide a seat hinge of the character above indicated which may be readily and conveniently assembled; and to provide a seat hinge assembly made of stamped sheet metal with its consequent economical manufacturing cost.

An illustrative embodiment of the invention is shown in the accompanying drawings wherein:

Figure 1 is a fragmentary side elevational view of an opera chair;

Figure 2 is a sectional view taken on line 2—2 of Figure 3;

Figure 3 is a sectional view taken on line 3—3 of Figure 2;

Figure 4 is a sectional view taken on line 4—4 of Figure 2;

Figures 5 and 6 are perspective views of a yoke member and its attaching plate for assembling the hinge to the seat supporting channel bar;

Figure 7 is a fragmentary view of the seat supporting channel bar;

Figure 8 is a view of a modification of the structure shown in the Figure 2 and taken on line 8—8 of Figure 9; and

Figure 9 is a modification of the structure shown in Figure 4 and taken on line 9—9 of Figure 8.

Referring to the drawings, a seat end standard comprises a central panel 1 supported by a pair of oppositely disposed legs 2, 3.

A pair of cupped members 4, 5 are identically formed, preferably of stamped sheet metal, and each is provided with an axially disposed opening 6, 7. They are secured together adjacent their rims by rivet pins 8, 9 to form a housing and bearing surface for a friction hinge member hereinafter more fully described. Each of the cupped members are also provided with three integrally formed ears 10 equally spaced from each other about the periphery of the rims of the cupped members. These ears are provided with bolt or

screw receiving apertures whereby the housing is secured to the panel 1 of the seat end standard by screws 11.

Within the housing formed by the assembled cupped members are a pair of identically formed discs 12, likewise preferably of stamped sheet metal. These discs are each provided with peripheral bearing flanges 13, 14, a pair of oppositely disposed arcuate slots 15 concentric with said flanges through which the rivet pins 8, 9 pass, and a centrally disposed non-circular opening 16, here shown as squared, and having laterally disposed flanges 17, 18.

A squared tubular shaft 19 is of substantially the same size and is secured within the centrally disposed opening of the discs by suitable means such as by spot welding for rotating the discs within their housing through an arc limited by the movement of the rivet pins 8, 9 within their respective arcuate slots 15.

A channel bar 20, for supporting a seat 21 secured thereto by suitable means such as screws 22 passing through holes 23 thereof, is provided with lug receiving apertures or slots 24 and a yoke 25 and its attaching plate 26 serve as a coupling to secure the tubular shaft 19 to the channel bar seat supporting member 20. This yoke is provided with integrally formed lugs 27 which register with the lug receiving apertures or slots 24 and are adapted to be inserted therethrough and riveted to the channel bar. A bolt 28 passing through the holes 29, 30 and 31 of the yoke, shaft and plate respectively provides ready and convenient means for assembling the structure.

It is frequently desirable to install seats of the opera chair type in arcuate rows. It will be noted that the peripheral bearing flanges 13, 14 of the discs are of less width than the internal width of the housing within which they rotate. As shown in Figure 4, provision is thus made for installation of these seats in arcuate rows.

As hereinbefore indicated, the structure shown in Figures 8 and 9 is a modified form of hinge in which similar parts are decimaly indicated. The modified form here shown

has a pair of identically formed cupped members 4.1, 5.1, each provided with a pair of oppositely disposed cam surfaces 100 along their inner peripheral edges.

Instead of the discs 12, the modified form has a pair of members 12.1 of the form shown and having peripheral bearing flanges 13.1, 14.1 and oppositely disposed arcuate openings 15.1 instead of the slots 15. The peripheral edges of these arcuate openings are concentric with the bearing flanges 13.1, 14.1 and the peripheral edges are adapted to slidably engage the rivet pins 8.1, 9.1.

The members 15.1 likewise have cammed surfaces 101 and when rotated by the raising or lowering of the seat gradually engage the cammed surfaces 100 of the cupped members 4.1, 5.1. The metal to metal contact of the pins 8, 9 against the ends of the slots 15 and the resulting noise which might occur in construction shown in Figures 1 to 4 is thus eliminated by the cam action above described in the modified form shown in Figures 8 and 9.

It will thus be seen that the seat hinge herein shown and described is adjustable with respect to arcuate seating, that the structure may be readily and conveniently assembled and that the seat hinge assembly can be easily made from stamped sheet metal with consequent economical manufacturing cost.

While but one specific embodiment of this invention has been herein shown and described, it will be understood that numerous details of the construction shown may be altered or omitted without departing from the spirit of this invention as defined by the following claims.

I claim:

1. In a device of the class described, a pair of discs provided with peripheral bearing flanges, a pair of cupped members secured together adjacent their rims and forming a housing and bearing surface for said bearing flanges, and an axially disposed shaft associated with said discs for rotating them within said housing.

2. In a device of the class described, a pair of sheet metal discs formed with peripheral bearing flanges, a pair of sheet metal cupped members secured together adjacent their rims and forming a housing and bearing surface for said bearing flanges, and an axially disposed shaft connected with said discs for rotating them within said housing.

3. In a device of the class described, a pair of sheet metal discs formed with peripheral bearing flanges and a centrally disposed non-circular opening, a pair of sheet metal cupped members secured together adjacent their rims and forming a housing and bearing surface for said bearing flanges, and an axially disposed shaft adapted to fit with said non-circular opening of said discs for rotating them within said housing.

4. In a device of the class described, a pair of sheet metal discs formed with peripheral bearing flanges, an arcuate slot concentric with said flanges and a centrally disposed non-circular opening in one of said discs, a pair of sheet metal cupped members one having an axially disposed opening therein and secured together adjacent their rims by a pin extending through said arcuate slots, said cupped members forming a housing and bearing surface for said bearing flanges, and an axially disposed shaft adapted to fit within said non-circular opening of said disc for rotating them within said housing through an arc limited by the movement of said pin within said arcuate slots.

5. In a device of the class described, a pair of sheet metal discs formed with peripheral bearing flanges, a pair of sheet metal cupped members secured together adjacent their rims and forming a housing and internal bearing surface for said bearing flanges, said rims when in assembled relation being of greater width than the width of said bearing flanges to provide a limited angular adjustability of said discs within said housing, and an axially disposed shaft connected with said discs for rotating them within said housing.

6. In a device of the class described, a pair of sheet metal discs formed with peripheral bearing flanges, oppositely disposed arcuate slots concentric with said flanges and centrally disposed non-circular openings, a pair of sheet metal cupped members having centrally disposed openings therein and secured together adjacent their rims by pins passing through said arcuate slots, said cupped members forming a housing and internal bearing surface for said bearing flanges and the rims thereof when in assembled relation being of greater width than the width of said bearing flanges to provide a limited angular adjustability of said discs within said housing, and an axially disposed shaft adapted to fit within said non-circular opening of said discs for rotating them within said housing through an arc limited by the movement of said pins within said arcuate slots.

7. The combination with a channel bar for a seat supporting member having a lug receiving aperture therein, of a seat hinge comprising a pair of discs provided with peripheral bearing flanges and a centrally disposed non-circular opening, a pair of cupped members having centrally disposed openings therein and secured together adjacent their rims to form a housing and bearing surface for said bearing flanges, an axially disposed shaft adapted to fit within said non-circular opening of said discs for rotating them within said housing, and a yoke embracing said shaft and provided with a lug adapted to be secured within the aperture of said channel bar.

8. In a device of the class described, a pair

of members formed with peripheral bearing flanges and oppositely disposed openings with peripheral edges concentric with said flanges, cammed surfaces at the opposite ends of said 5 openings, a pair of cupped members secured together adjacent their rims and secured together by oppositely disposed pins adjacent the peripheral edges of said oppositely disposed openings, said cupped members 10 forming a housing and bearing surface for the pair of said members, oppositely disposed cammed surfaces on the inner edges of said cupped members adapted to contact the cammed surfaces of said pair 15 of members, and an axially disposed shaft secured to said pair of members for rotating them within said housing through an arc limited by the said contacting cammed surfaces of said cupped members with the 20 cammed surfaces of said pair of members.

In testimony whereof I have hereunto set my hand at Grand Rapids, Michigan, this 30th day of October, 1930.

WALTER M. HANSON.
